FURRING AND FASTENING DEVICE

Filed Feb. 15, 1926

INVENTOR.
JOHN L. SULLIVAN.
BY *Joseph B. Gardner*
ATTORNEY.

Patented Nov. 15, 1927.

UNITED STATES PATENT OFFICE.

JOHN L. SULLIVAN, OF BERKELEY, CALIFORNIA.

FURRING AND FASTENING DEVICE.

Application filed February 15, 1926. Serial No. 88,232.

My invention relates to a device for positioning and securing plastering netting or the like in spaced relation to the wall of a building. More particularly the device is of the type broadly embraced in my Reissue Patent No. 16,103, and in general comprising a spacing member which is slidably mounted on a fastening member and normally held to resist removal therefrom and is arranged to cooperate with a projection on the latter whereby the netting wire may be gripped and held between such projection and the spacer after the device has been driven into position.

An object of the invention is to provide the device with a sheet metal spacing member which will not become loosened on the fastening member in the handling of the device.

Another object of the invention is to provide a spacer for the device which when operatively disposed will present a minimum interference to the keying of the plaster about the wire in the area of the device, and which at the same time will normally neither cut the netting wire nor injure the surface of the wall in the application of the device.

A further object of the invention is to provide the device with a spacer having the foregoing advantages and which will not spread or flatten on the wall when forced thereagainst.

The invention possesses other objects and features of advantage, some of which, with the foregoing, will be set forth in the following description of the preferred form of my invention which is illustrated in the drawings accompanying and forming part of the specification. It is to be understood that I do not limit myself to the showing made by the said drawings and description, as I may adopt variations of the preferred form within the scope of my invention as set forth in the claims.

Referring to said drawings:

Figure 1 is a perspective view of one embodiment of my invention.

Figure 2 is a longitudinal sectional view 50 of the device.

Figure 3 is a sectional view of a wall fragment showing devices positioned thereon both before and after being driven in final position.

Figure 4 is a transverse sectional view of 55 the device, taken through the fastener and spacer.

Figures 5 and 6 are perspective views of modified forms of the device.

In the embodiment of my invention as 60 illustrated in Figures 1 to 4, the device comprises a fastening member 6, which for simplicity of construction and cheapness of cost, may be in the form of an ordinary nail having the usual shank 7, pointed end 8, and 65 head 9. Associated with the fastener 6 is a spacing member 12 which is arranged to be normally carried by the fastener so that the fastener and spacer may be handled as a 70 unit. The spacer is preferably formed of a sheet metal blank which is folded upon itself to define opposed body portions 13 and 14. Formed in the spacer blank is an opening 16 which is located at the fold and positioned 75 immediately of the side edges 17 and 18 of said portions.

The fastener member 6 passes through the opening 16 and between the opposed portions of the spacer, the pointed end 8 being as here shown disposed adjacent the open 80 end 19 of the spacer. The portions 13 and 14 are arranged to resiliently and frictionally bear against the sides of the shank preferably from one end of the spacer to the other, and the portion of the portions at 85 the end 19 are arranged to engage the tapered sides 21 of the end 8 of the fastener. With the spacer portions thus gripping the shank, longitudinal displacement of the spacer on the fastener, particularly the slipping of the former toward the head 9, will be effectively resisted when the device is being handled, while on the other hand, when the device is being driven into position the spacer will readily slide on the shank. 90 Means are also formed on the spacer for preventing the shank, during the handling of the device, from moving into obliquity with the spacer especially in the plane of the body portions 13 and 14. As here shown, each 100

of said portions is formed with arcuate longitudinally-extending cavities 22 in which the shank is disposed and is resiliently held. This construction of the portions permits of the side edges 17 and 18 thereof being positioned in close proximity and thus materially increases the resistance of the spacer to bending or flattening during the application of the device.

10 The portions 13 and 14, as shown in Figures 1 and 2, are provided at the open end 19 of the spacer, with flanges 23 and 24 which extend outwardly at approximately right angles to the shank. These flanges provide flat bearing surfaces for engagement with the surface of the wall and prevent mutilation of the latter by the spacer when the spacer is forced thereagainst.

In the application of the device the spacer 20 is inserted between the wall 26 or building paper 27 and the reenforcing netting 28, the spacer being preferably so held that one of the wire strands 29 of the netting will seat in the depression 31 naturally formed in the 25 folded end of the spacer by reason of the distended portions 22. The fastener is then driven home and the netting wire will be firmly gripped between the spacer and the head, the latter now functioning as a wire-engaging element. It is to be particularly noted that although the portions 13 and 14 are drawn closely together and to the shank and thereby rendering the spacer quite thin, the folded and distended portion of the 30 spacer is presented to the netting wire and no shearing of the wire between the spacer and head will take place.

In the embodiment of the invention shown in Figure 5, the bearing flange of one body member 131 is omitted. In Figure 6, the spacer is likewise shown with one of the flanges removed, however, the flange 24' which is retained, is bent to extend under the member 13' from which the flange has been omitted, and furthermore said flange is 45 perforated for the reception of the shank.

I claim:

1. In a device of the character described, an oblong strip of sheet metal having 50 parallel side edges, arcuated centrally in cross section and folded together longitudinally substantially equi-distant from its ends, thereby forming a spacing element comprising a central cylindrical portion having on opposite sides projecting web portions, and a driven element projecting axially through said cylindrical portion, said driven element having a head at its upper end adapted to engage and bind a lath wire on the spacing element adjacent the intersection of said cylindrical portion and one of said web portions.

2. In a device of the character described, a spacing element formed of a strip of flat metal folded together longitudinally thereby

forming a pair of lath supporting sections, each of said sections having a recess formed in its upper end intermediate its side edges, thereby forming lath retaining projections and lath seats therebetween, and a cooperating nail projecting vertically through said spacing element between said supporting members, said nail having a head the margin of which extending outwardly beyond the sides of said supporting members but not 75 extending to the side edges thereof, said head adapted to operatively engage and bind a lath wire on one of said lath seats intermediate one of said lath seats intermediate one of said projections and the body portion 80 of said nail.

3. A wire fastener comprising, a spacing element formed of an oblong strip of flat metal folded together longitudinally, thereby forming a pair of lath supporting members disposed in parallelism, a vertically extending groove formed on the inner side of each of said members, thereby forming generally a cylindrical opening extending substantially from the top to the bottom of the 90 spacing element between said members, the side edges of said grooves terminating short of the side edges of said members, and a driven element projecting through said grooves and engaging opposite sides thereof 95 substantially throughout their lengths for holding said driven element in suitable axial alignment with the spacing element.

4. A nail, a lath supporting section disposed in a plane extending through said nail 100 and having an intermediate portion bent to extend around one side thereof and bearing thereagainst, and a lath supporting section disposed in a plane extending through said nail and having an intermediate portion bent 105 to extend around the other side thereof and bearing thereagainst, said sections integrally connected together at registering ends, said nail and said sections adapted to coact for binding a lath wire therebetween for attaching it to a support outstandingly therefrom.

5. A wire fastener comprising, a spacing element formed of a strip of flat metal doubled together flat ways and provided with a central concavo-convex groove, thereby 115 forming a pair of lath supporting sections disposed in parallelism and having a nail opening extending therebetween, and a cooperating nail projecting through said opening and bearing against the sides thereof to 120 resist removal therefrom, said sections adapted to coact for engaging and holding a lath wire in spaced relation with a support.

6. In a device of the character described, an oblong strip of sheet metal having parallel 125 side edges, arcuated centrally in cross section and folded together longitudinally substantially equi-distant from its ends, thereby forming a spacing element comprising a central cylindrical portion having on opposite 130

sides projecting web portions, and a driven element projecting axially through said cylindrical portion, said driven element having a head at its upper end adapted to engage and bind a lath wire on the spacing element adjacent the intersection of said cylindrical portion and one of said web portions, said

spacing element having a flat bearing portion at its lower end extending substantially at right angles. ¹⁰

In testimony whereof, I have hereunto set my hand at Oakland, California, this 4th day of February, 1926.

JOHN L. SULLIVAN.
